CLAIM

The ornamental design for a wind direction indicator, as shown and described.

DESCRIPTION

FIG. 1 is a top perspective view of a wind direction indicator showing my new design;

FIG. 2 is a top perspective view thereof from the side opposite that shown in FIG. 1;

FIG. 3 is a side elevational view thereof with the mounting bracket omitted; and

FIG. 4 is an end elevational view thereof from the right of FIG. 1.

FIG. 1

FIG. 2

FIG. 3

FIG. 4
